UNITED STATES PATENT OFFICE.

AUGUSTUS JOUAN, OF SAN FRANCISCO, CALIFORNIA.

DEEP-SEA-SOUNDING APPARATUS.

Specification of Letters Patent No. 22,877, dated February 8, 1859.

To all whom it may concern:

Be it known that I, AUGUSTUS JOUAN, of San Francisco, in the State of California, have invented an Improvement in Automatical Apparatus for Deep-Sea Soundings; and I do hereby declare the following to be a full and exact description thereof, reference being had to the accompanying drawings and to the letters and marks thereon.

10 Of the drawings forming part of this specification Figure A represents a vertical section through the instrument: Fig. B a full sized upper end view of a six foot instrument: Fig. C a full sized lower end view 15 of a six foot instrument: Fig. D a full sized sectional view of the compartment for locating the sediment from the bottom.

Numbers 1, 2, 3, 4 represent as herein described.

20 It makes two circular conical parts united at their base.

The main body of this apparatus is hollow of iron; it could be made of steel or of other metals, and such, being, for instance, 25 six feet in length, ten inches in diameter in the center and otherwise similar in forms, as shown by the drawings, would be of a convenient size for sounding in all depths. It should be constructed of three longitudinal equal parts, sections, about half an inch 30 in thickness at the center, in the central piece of section, and thence diminishing to about a quarter of an inch at the extremities, and made so, as to join and form homogeneity after being brazed together, for the 35 purpose of increasing their power of resistance to an outside pressure; at the point of union of the several parts or sections, I make a ridge or thickening for strengthening the 40 whole. It should be covered with an envelop of pure native gutta-percha or caoutchouc of about half an inch in thickness, for keeping the water from filtering in and likewise for increasing the buoyancy of the 45 instrument.

After the instrument is made, every part of it, is firmly adherent together. It can be exteriorly thickly coppered or bronzed and the inside of its tube likewise, by the process 50 of galvanoplastic, but provided the instrument is not of cast iron.

It can be made of solid wood, for instance, 55 of one piece of yellow pine, choosing a piece of a young tree, which by its natural full growth, should be in diameter, a few inches above the diameter required for the instru-

ment, so that the reduction can be brought to a convenient diameter following the natural fibers and circular growth of the tree. Having thus acquired the desired dimensions, the block of wood must be plunged 60 in a cylinder of sufficient resistance and full of oil, and there to receive a pressure equal to that of about five hundred atmospheres, by means of a hydraulic press, in which 65 oil is used instead of water, to the effect of filling with that substance, the pores of the wood. The block thus prepared should be enveloped with vulcanized gutta percha or caoutchouc of a thickness of about one 70 eighth of an inch for an instrument of six feet.

At the upper end of the instrument is a ring for attaching means for lowering the apparatus to the edge of the water in the 75 act of sounding or to connect with a line. At about one third of the whole length, from the lower end are metallic rigid rings, for the purpose of suspending the ballast.

On a circular line corresponding with the 80 upper part of the concavity of D are small holes (4) to let out the water when the sediment enters the tube. Near the bottom part of D are elastic metallic blades, for the purpose of detaining by their elasticity the sediment when it enters the tube. 85

In the center of the instrument, made either of iron, wood or other material, is a metallic conical tube, passing longitudinally from one end to the other, with a division 90 in its center, and with it are firmly connected (1 and 2) covers, each one composed of a metallic cap, a plug of metal or other materials and a circular plate or disk of caoutchouc, differing one from the other, only 95 in regard to the inclination of the plug and in the quality of the caoutchouc, that of (1) being of native unmixed and (2) of vulcanized or of metal; one of the plates having to float and the other to sink, a metallic block (3) which I denominate permanent ballast, with a tubular conical aperture in its center; a compartment D with metallic elastic blades.

D and 3 are made separate, but must be 105 adapted to the part of the tube, where it corresponds, so that after being placed and brazed, they will strongly adhere with the main tube.

To an instrument six feet in length, with 110 other dimensions as herein described and as a standard scale for all sizes; the tube

at the smallest extremity (that intended to stand up when the instrument is immersed) should be about three quarters of an inch in diameter, at the other extremity about 5 three inches.

The cover (1) should be made of a form convexo-concave, with a circular hole cut conically in its center; in thickness about half an inch and so as to fit and stand on 10 the head of the tube, where it is to be screwed and firmly connected.

The cover (2) connecting with the neck inside of D is in form similar to the other, though not as heavy in metal and of less 15 area.

The plugs are of lead, they could be made of other substance, they are of conical form, combining with that of the holes, but their lengths and inclinations of their sides, 20 should be according to the resistance, which they are intended to make.

The circular plate or disk of native caoutchouc in connection with (1) should be in diameter about five eighths of an inch 25 and three eighths of an inch in thickness. The plate in connection with (2) of vulcanized caoutchouc or of metal should be smaller.

When sounding with the instrument left 30 to its own action, without the use of a line, ballast (which I name detachable ballast) should be added and that by means of hanging weights, as shown by the drawings, and that ballast should be of a weight two 35 pounds (net) over that which would be necessary to maintain the instrument completely immersed, though not sinking: for instance, an instrument six feet in length, otherwise as herein described, displaces 40 about thirteen gallons of salt water, or about one hundred and thirty pounds weight. Of that weight I allow:

90 lbs. for the longitudinal sectional parts
45 25 " for tubes, covers, &c.
6 " for permanent ballast
13 " for detachable ballast

134

50 allowing two pounds over, to balance the displacement of the detachable ballast. Therefore an apparatus as here described and weighing 134 lbs. would be ready for sounding. Its permanent weight would be 55 120 lbs. and with that weight, about one eighth of its length would float.

It is indispensable that the instrument when immersed stands in a perpendicular position and for that object is the permanent 60 ballast (3) inside of the tube, and the weight of that permanent ballast added to that of the other parts of the instrument must be sufficient to bring it to its permanent bearings or seven eighths immersed and likewise to stand in a perpendicular position,

Should the displacement of the instrument produce more than thirteen gallons or otherwise 130 lbs., the surplus weight should be applied in increasing the thickness of the longitudinal sections.

70

The detachable ballast consists of metallic blocks, in connection with metallic rods, which at one extremity, are bent in the form of a hook.

The rods must be stiff enough not to bend 75 under a certain vertical pressure and their lengths must be such that, when hooked to the rings, the lower parts of the blocks, will reach about two inches, below the lower extremity of the tube.

80

The form of the ballast can vary from that shown by the drawings, but the form if differing, yet must be such that when striking bottom and the ballast has separated from the main body, that ballast will not stand in an upright position, to avoid the risk of being hooked again, when the instrument will be rising.

85

The instrument can be made of different forms and dimensions; should the dimensions be much increased, the detachable ballast might be composed of common stones, for instance, inclosed in boxes, made to connect with the rings, by means of iron rods, but the bottoms of these boxes should be in 90 accordance with what is said in regard to metallic ballast.

95

When using a line, a supplementary ballast, equal to two-thirds of the weight of the water displaced by the rope should be added.

100

A line of a small diameter, such as the one used in Lieut. Brooke's sounding apparatus, would be sufficient, its only use being to guide the instrument toward the vessel and help in measuring the depths.

105

The rope should always be moistened before using it for sounding, and should be of a greater length than the supposed depth of soundings.

110

Modus operandi: The valve, plates or disks are put in their tubes, both caps (covers) are screwed tight; the plugs are set firm, minding that the plug which goes in (2) be that of lesser inclination. In

115

sounding without a line, the apparatus is lowered down to the surface of the water and then let go. It sinks with regularity, increasing progressively its velocity. Arriving at a certain depth, the plug (2) is forced into the tube, which instantly fills with water and the valve, plate or disk of vulcanized caoutchouc or of metal, closes the opening and that water is isolated.

120

At a greater depth, the plug (1) is forced into the tube and this likewise fills with water, and then the plate of native caoutchouc floats and closes the opening and that water is likewise isolated. Immediately the instrument ascends, though with a moderate velocity; its velocity increases progressively

125

130

till the instrument has sprung out of water. The entire time of immersion is then known, and it is the departure for calculating the depths.

5 Tables will be prepared for calculating the depths by the interval of immersion, with an apparatus of definite form, but such tables, for instance, prepared for an instrument at herein described with two 10 pounds over weight, making altogether thirteen pounds of detachable ballast, would not be applicable to an instrument of a globular or any other form, neither to one with more than two pounds over weight, nor 15 to one with more or less ballast than thirteen pounds.

The velocity of immersion being governed by the quantity, of weight over and the velocity of ascension by that of the 20 weight of ballast discharged and likewise in either cases, the form of the instrument will have an influence.

An instrument of six feet and similar in 25 form to the within description, will bring up, in the upper tube, about eight ounces of water, in the lower tube, about six ounces and about one pound of sediment from the bottom and it might be disposed to bring a greater quantity of sediment.

30 Supposing the depth to be three miles, I estimate that an apparatus six feet in length and as described, will travel that distance and back (six miles) in the interval of about six minutes.

35 In great depth, the instrument when abandoned to its own action, will emerge to the surface at a place distant from that

where it was immersed, but the distance would not be such that the instrument would not be visible with naked eye from the 40 vessel, specially as the instrument will travel with great velocity and surging with an additional power from its transition of elements, it will spring at a considerable height and moreover; deep soundings are only 45 attempted in good weather and when the ship can be hove to, without much drifting. This mode of sounding will guide to a closer approximation of the depths, than any one known, yet the result will only be a nearer 50 approximation, the most accurate mode of finding the depths, would be by ascertaining the highest pressure, received by the instrument during the operation.

The upper cover (1) with a long and 55 graduated conical plug, might be employed for testing the highest pressure, received during the immersion, as shown in red ink in the drawings.

I do not claim, the external form of the 60 instrument, neither the mode of calculating the depth by the time of submersion, neither that, as set forth, for testing the highest pressure.

I claim as my invention and desire to secure by Letters Patent—

The combination and arrangement of the several essential devices described, operating in the manner and for the purposes set forth.

A. JOUAN.
